UNITED STATES PATENT OFFICE

JOHN S. GREENE, OF ROCHESTER, NEW YORK, ASSIGNEE TO PHOTOSTAT CORPORATION, OF PROVIDENCE, RHODE ISLAND, A CORPORATION OF RHODE ISLAND

PHOTOGRAPHIC PRINT EXPOSING AND HANDLING APPARATUS

Original application filed May 12, 1923, Serial No. 638,644. Divided and this application filed August 29, 1928. Serial No. 302,807.

My present invention relates to photography and more particularly to machines of the character known as commercial cameras for photographing records of documents and other small objects, and it has for its object to provide a simple, efficient and serviceable apparatus of this kind offering greater convenience in operation and manipulation in the exposing, developing and drying of 10 the photographic sensitive material, the purpose of the machine being to finally deliver the completed print in a dry condition.

This application is a division of my prior application, Serial No. 638,644, filed May 12, 15 1923, now Patent No. 1,683,883, issued September 11, 1928, entitled "Photographic print drying apparatus" in which the showing is substantially the same but in which I have claimed the drying apparatus per se. 20 The present subject matter, as above stated, relates broadly to the general combination of a drier associated in a particular manner with the other mechanisms which operate upon the print, the whole being made available as a continuous process.

To these and other ends the invention resides in certain improvements and combinations of parts, all as will be hereinafter more fully described, the novel features being 25 pointed out in the claims at the end of the specification.

In the drawings:

Fig. 1 is a side elevation of a camera provided with automatic developing means and 30 fitted with a drying apparatus constructed in accordance with and illustrating one embodiment of my invention;

Fig. 2 is an enlarged central section through the dryer and a fragment of the adjacent 35 developing apparatus;

Fig. 3 is a rear view of the dryer;

Fig. 4 is an enlarged view of a portion of a conveyor showing one of the sheet carrying devices in detail, and

Fig. 5 is a horizontal section on the line 40 5-5 of Fig. 2.

Similar reference numerals throughout the several views indicate the same parts.

As before stated my invention concerns 45 commercial cameras in which sensitive paper

in the continuous roll is exposed, severed, developed and fixed through the use of a semi-automatic developing apparatus from which it is delivered either washed or unwashed ready for drying. Such a machine is shown 50 in my prior Patent No. 1,421,079 June 27, 1922. There is therein shown a plurality of tanks and a tray or other final depository for the prints all arranged in a small dark room. After the print has been severed it is picked 55 up by an endless conveyor provided with suitable impaling devices for the purpose and carried through the several tanks after which it is deposited in the tray in a wet condition. The present invention contemplates 60 providing for the developing apparatus an improved construction of drier into which the washed print is carried by the conveyor and thoroughly dried before being returned to the tray or depository.

Referring to the drawings 1 indicates generally a familiar type of commercial camera supported on a stand or table 2. The developing apparatus embodied therein comprises a housing 3 beneath the camera body 70 forming a dark room in the bottom of which are three vertical tanks 4, 5 and 6 constituting respectively the developing bath, the fixing bath and the rinsing bath, the latter only with the rearward portion of the dark room 75 being shown in Fig. 2. Running through the dark room near the bottom thereof is a conveyor consisting of side chains 7 running over sprockets 8 and thence around sprockets 9 at the bottoms of the respective tanks. Connecting the side chains 7 of the conveyor at 80 intervals are a plurality of cross bars 10 each provided with a plurality of impaling devices 11 having the present form of barbed spurs or pins as best shown in Fig. 4. The exposed print after being severed in the camera at the front end of the dark room is 85 picked up by one or another of these impaling devices in a manner explained in my said prior patent but not of interest here and is retained on the carrying bar at its forward edge in the manner indicated in Fig. 4 wherein a fragment of the sheet is shown at A. After emerging from the washing tank 6 into which it is thus drawn by the conveyor, 90

the sheet or print passes between rolls 12 at the rear end of the dark chamber 3 (one of which is fitted with sprockets 13 for the conveyor chains) and out through a narrow 5 slotted opening 14 in the rear wall of the dark chamber to the drier hereinafter described.

In the practice of my invention I attach to the rear end of the dark chamber housing 3 the brackets 15 or otherwise a drying apparatus 10 embodying a downwardly extending casing 16 which is independent of the stand or table 2 for the reason that it must move with the housing 3 as the camera is focused. Within this casing is a series of inclined slides 17 15 in zigzag arrangement so that the lower end of one is in position to deliver to the upper end of the next lower one. These slides are supported at their upper ends on the walls of the casing including a partition wall 18 20 and at their lower ends upon transverse shafts 19 and are of such a nature as to permit the free passage of air upwardly through the chamber. In the present instance the slides consist of rods or wires as shown in dotted 25 lines in Fig. 3. Turning on the shafts 19 near their ends are sprockets 20 for the conveyor chains 7 so that the latter carry the wet print downwardly dragging it from one to another of the slides upon which it rests 30 and finally across slides 21 on a false bottom 22 with which the casing is provided. From thence the conveyor passes around a sprocket 23 and upwardly behind the partition wall 18 to carry the print through a slotted opening 24 at the top of the casing 16 where it travels around sprockets 25 supported on brackets 26 and finally passes forwardly back into the dark chamber 3 at the top thereof through a slotted opening 27 being deposited 35 40 therein if desired in the manner set forth in my said prior patent.

The print dries during its travel down through the casing 16 being exposed to a circulation of air on both sides and to hasten 45 this drying action I provide for a forced circulation of warm air within the casing. Between the false bottom 22 and the bottom 28 is a chamber 29 containing a fan or blower 30 rotating on a vertical axis to force a current of air upwardly as shown by the arrows 40 through an opening 31 in the false bottom 22. This air is drawn in to the chamber 29 through suitable lateral openings 32 in the casing and, before reaching the blower, 55 passes over heating elements 33 in the present form of electrical heating coils having the terminals 34. Baffles 35 at the sides of the blower cause the air to pass through the coils to the opening 31 and the blower is 60 mounted with its motor on a platform 36 extending between the baffles.

The conveyor chains 7 are driven through a motor 37 (Fig. 1) through a shaft 38 (Fig. 2) provided within the dark chamber 3 with 55 sprockets 39.

In the practice of my invention, I thus provide in combination a camera, a developing apparatus and a dryer, through all of which a print is successively passed by means of a conveyor as a continuous operation being delivered in a dry and finished state without requiring further manipulation of any kind. 70

I claim as my invention:

1. In a photographic apparatus including a frame, a camera body mounted on said frame and movable thereon for focusing, and a dark chamber attached to said camera body and containing photographic print developing apparatus, said camera body and dark chamber being movable together as a unit when said body is shifted for focusing, the combination with print drying apparatus mounted on said dark chamber exteriorly thereof and movable as a unit therewith, of print conveying mechanism for moving a developed print from said dark chamber to said drying apparatus. 80

2. In a photographic apparatus including a frame, a camera front and lens supported from said frame, a camera body having a focal plane support therein mounted on said frame for movement along said frame for focusing, and a dark chamber containing photographic print developing apparatus attached to said camera body and movable along said frame as a unit therewith, the combination of print drying apparatus mounted exteriorly of said dark chamber and secured thereto to move along said frame as an integral unit with said dark chamber and camera body when the latter is moved for focusing, and print conveying mechanism for moving an exposed print through said developing apparatus and to said drying apparatus. 90
